(57) **CLAIM**

The ornamental design for an electronic cigarette necklace, as shown and described.

DESCRIPTION

FIG. 1 shows a perspective view of an electronic cigarette necklace of the present invention.

FIG. 2 shows a front view thereof.

FIG. 3 shows a rear view thereof.

FIG. 4 shows a left-side view thereof.

FIG. 5 shows a right-side view thereof.

FIG. 6 shows an overhead view thereof; and,

FIG. 7 shows an underside view thereof.

The electronic cigarette necklace is shown with a symbolic break in its length. The appearance of any portion of the article between the break lines forms no part of the claimed design.

The broken lines in the drawings depict portions of the electronic cigarette necklace that form no part of the claimed design.
